UNITED STATES PATENT OFFICE

127,850

DESIGN FOR A LAMP

Joseph J. Clement, Milwaukee, Wis.

Application March 15, 1941, Serial No. 99,633

Term of patent 14 years

To all whom it may concern:

Be it known that I, Joseph J. Clement, a citizen of the United States, residing at Milwaukee, in the county of Milwaukee and State of Wisconsin, have invented a new, original, and ornamental Design for a Lamp, of which the following is a specification, reference being had to the accompanying drawing forming part thereof.

In the drawing in which the shade, structure therein, and ball are shown in dotted lines, and in which the characteristic features of my design are shown in full lines, Fig. 1 is a side elevational view of a lamp showing my new design, and Fig. 2 is a front elevational view thereof.

I claim:

The ornamental design for a lamp, substantially as shown and described.

JOSEPH J. CLEMENT.
